UNITED STATES PATENT OFFICE

LOUIS FORDE MONYPENNY, OF TORONTO, ONTARIO, CANADA, ASSIGNOR TO MONYPENNY BROS. LIMITED, OF TORONTO, ONTARIO, CANADA

UNDERGARMENT

Application filed April 23, 1929, Serial No. 357,521, and in Canada May 18, 1928.

My invention relates to improvements in undergarments and relates more particularly to union garments, and one of the objects of the invention (whether the garment be provided with buttons or not) is to provide for the necessary elasticity both vertically through the center of the back particularly in a line with the crotch, and to some extent horizontally without using an elastic waist band, thereby enabling me to extend the opening in the back of the garment right up to the waist line which is a point markedly higher than is reached with garments of this class that are provided with an elastic waist band, and so provide the maximum opening in the seat of the garment without subjecting the garment to rupturing strain, notwithstanding the posture of the wearer. Another object of the invention is to connect the lower portion of the elastic material used in the back of the garment to the upper portion of the seat of the garment in a particular manner so that the said elastic material will be united with the garment at the place where it is subjected to the greatest strain without any possibility of the same being cut or torn in use.

A still further object of the invention is to provide a garment of the class set forth (and this is to be construed as applying to a garment of the type specifically illustrated in the drawings forming part of this specification, or to undergarments provided with partial or full length sleeves and legs) which can be worn and permit the wearer all necessary bodily movements without subjecting the garment to any rupturing strain, and one that can be more cheaply manufactured without sacrificing quality than competing garments, and in the following specification and the drawings forming part thereof I shall describe and illustrate my preferred form of invention and a modification thereof, and what I claim as new will be set forth in the claim forming part of this specification.

Figs. 1 and 2 illustrate a rear view of a garment to which my invention is applied, Fig. 1 showing the garment complete, and Fig. 2 showing the first step in sewing the reinforcing band in place. Fig. 3 is a vertical central longitudinal section, on a greatly en-

larged scale, on the line 3—3, Fig. 1. Fig. 4 is a horizontal cross section on the line 4—4, Fig. 1, on a greatly enlarged scale. Fig. 5 is a rear view of the upper portion of the back of the garment showing a modification 55 hereinafter more particularly referred to, and Fig. 6 is a vertical section, on a greatly enlarged scale, on the line 6—6, Fig. 1.

In the drawings, like characters of reference refer to the same parts. 60

In various makes of undergarments of the class set forth elastic webbing is inserted in the back of the garment, and also elastic webbing is inserted at the waist band. I have found from exhaustive experiments that 65 elastic webbing at the waist band necessarily curtails the vertical height of the opening in the seat because said webbing invariably extends some distance below the waist line. Now in order that the garment be not subjected to rupturing strain particularly when the wearer assumes a sitting posture with the opening in the seat fully extended, it is necessary that the top of said opening be extended substantially to the waist line, and that the 70 necessary elasticity required in the back of the garment under the conditions noted, shall be provided solely by the elastic insert in the back of the garment, and the width of the bottom of said insert must be such as to extend a considerable distance beyond both sides of 75 a central line passing vertically through the crotch, because while the greatest extension of the garment at the back is substantially in the direction of said line, extension also occurs at both sides of said line because the upper portions of the interior and posterior flaps are sewn to the lower part of the elastic insert for some distances at each side of said vertical line. Therefore it follows that the 80 width of the lower portion of said elastic insert to provide a garment having the wearing comfort of my garment must be wider than the overlapping upper ends of said flaps. 85

2 and 3 are the two-body parts of the rear of the garment, and 4 and 5 are the two-rear leg parts. 90

The front of the garment is not illustrated, but may be of the usual construction and parts, and these are joined to the parts illus- 100

trated in any manner well-known in the art. 6 is the interior flap and 7 the posterior flap. As will be seen from Figs. 1 and 2, and particularly Fig. 3, the upper portions of the 5 said flaps overlap and upon referring to Fig. 2 particularly it will be seen that these upper portions extend substantially equal distances beyond each side of the central line 8 passing longitudinally centrally through the 10 garment and bisecting substantially the crotch.

9 is the insert made of elastic material which extends from the waist line to the neck. The sides of this insert are coupled to the 15 body parts 2 and 3 in any well-known manner, preferably by using a two-needle machine (see Fig. 4). The neck end of the insert is preferably turned inwardly as shown at 10, and a facing or binding 11 is secured there- 20 over as shown clearly in Fig. 3. The lower edge portion of the insert 9 is suitably secured to the upper portion of the rear leg parts 4 and 5, and my preferred construction for this purpose consists in binding the said 25 lower edge 12 between the upper portions 13 of the rear leg parts 4 and 5 and the inturned hem 14 thereof, which inturned hem rests in contact with the insert 9. Where the upper portions of said rear leg parts 4 and 5 30 overlap, as shown in Fig. 3, the upper portion of the posterior flap 7 encloses the parts illustrated in Fig. 6, and the hem 14' of said posterior flap rests in contact with the insert 9. The parts described are united preferably 35 by a two-needle machine, thus making the two lines of parallel stitchings 15 and 16. In practice I have found that the insert 9 when united to the upper portions of the rear leg parts 4 and 5 as described will not stand the 40 strain to which the garment is subjected, and therefore the lower portion of said insert must have a reinforcing connection with said rear leg parts. This reinforcement is preferably in the form of a piece of tape 17. In 45 applying the same, it is sewn by the stitching 18 of a single-needle machine to the waist band 19 as shown in Fig. 2. The ends of the tape 17 are turned in, and the reinforcement moved into the position shown in Fig. 1, and 50 the free longitudinal edge *c* thereof turned under and sewn in place by the stitching 20 of a single-needle machine. 22 is the stitching attaching the ends of the reinforcement in place.

55 Figs. 1 and 3 show clearly that the stitchings 18 and 20 are spaced a considerable distance apart: in other words, the said reinforcement overlaps well the extreme lower portion of the insert 9. Only one line of single stitching 20 passes transversely through the insert 9, and therefore when said insert is elongated, the strain is divided between the stitchings 15, 16, 18, 20 and 22, and consequently the threads in the weave of the insert 9 are not subjected to rupturing strain.

As before-mentioned, the reinforcement or tape 17 is sewn in place by means of a single-needle machine, and this machine is so adjusted that the length of the stitches will be longer than the stitches of the two-needle machine so that there will be substantially no severing or cutting of the fibres of the insert 9 by reason of these longer stitches that would materially weaken or impair the strength of the said insert. 75

It will be understood by one skilled in the art, that the ribs or wales of the insert 9 extend substantially parallel with the waist band 19.

I prefer to shape the insert 9 substantially like the inverted letter V, because this shape obviates the use of an insert shaped for example, like that shown in Fig. 5 where the material between the dotted lines *a* and the full lines *b* appears to be unnecessary to the 80 full comfort of the wearer. Particularly in warm weather, the lesser the amount of elastic material 9 (which of course is preferably knitted goods) in contact with the body, the greater comfort will the wearer experience. 90 But it must be understood that I do not confine myself to any particular shape of insert in the back of the type of garment herein referred to which will function after the manner herein disclosed. 95

For the purposes of this specification, in Fig. 3, I have shown the stitchings 16, and 18 as spaced apart, though in practice, the stitching 18 may lie over the stitching 16 as shown in Figs. 1, 2 and 5. 100

It is evident that I have disclosed in the specification and the drawings forming part thereof a new principle in constructing garments of the class set forth in that I show clearly that provided the lower portion of the elastic insert extends beyond the attached upper portions of the interior and posterior flaps, that elastic bands can be dispensed with, because the said insert performs the additional function of said elastic bands, and therefore it is bi-functional in character. In other words, I have to the extent indicated, reorganized the component parts of a garment of the class set forth resulting in a garment of a lesser number of parts which 105 possesses all of the functional value of the greater number of parts composing garments of this character heretofore invented, and have reduced the cost of manufacture of this type of garment as a result without any 110 impairment in quality, but with a most marked improvement in wearing comfort. 115

Obviously any suitable or well-known method of building a garment embracing the principle of that herein disclosed may be carried out without departing from the scope of the appended claim. 125

I do not confine myself to using the reinforcement 17, because further experiment may enable me to secure a suitable elastic 130

material for the insert that will not cut or pull away where it is attached to the upper portions of the rear leg parts.

Nor do I confine myself to extending the insert 9 or its equivalent right up to the neck band, because garments worn by persons of slight build are not required to stretch in the back to the same extent as those worn by stout persons.

10 The elastic insert located as I use it keeps the flaps normally closed, so consequently there is no buckling or wrinkling of these parts to cause inconvenience to the wearer.

What I claim as my invention is:

15 A union garment of the character described, comprised of relatively inelastic fabric having an upper centrally-divided body portion, rear leg parts secured at their upper portions to said body portion, each leg part being provided with a flap forming an opening in the seat of the garment, one of said flaps overlapping the other, the flaps being of substantially triangular formation with their wider ends disposed at the tops thereof adjacent 20 the waist line of the garment, an elastic insert extending longitudinally of the upper body portion with its side edges diverging downwardly and said side edges connected to the edges of the divided portions of said body portion, a connection between the lower edge of the insert and adjacent edges of the leg parts, the width of the lower edge of the insert being such as to extend beyond the outer ends of the overlapping seat flaps, and a reinforcing element extending transversely across the back and united at its lower edge to the upper portions of the leg parts at the waist line and united at its upper edge to said insert and the ends of the reinforcement being secured to inelastic portions of the garment.

LOUIS FORDE MONYPENNY.
